H. HOLDING.
TENNIS RACKET.
APPLICATION FILED FEB. 18, 1918.

Patented Jan. 21, 1919.

UNITED STATES PATENT OFFICE.

HENRY HOLDING, OF NEW YORK, N. Y.

TENNIS-RACKET.

1,292,317.

Specification of Letters Patent. Patented Jan. 21, 1919.

Application filed February 18, 1918. Serial No. 217,799.

To all whom it may concern:

Be it known that I, HENRY HOLDING, a citizen of the United States, and a resident of the borough of Manhattan, city, county, and State of New York, have invented certain new and useful Improvements in Tennis-Rackets, of which the following is a specification.

My improvements relate to the hand bats or rackets used more particularly in the game of tennis, consisting of an elliptical or oval rim attached to a handle, the elastic resilient medium for contact with the ball being formed of strands of catgut strung upon and within the rim so as to afford a flat, taut reticulated striking surface.

Ordinarily the catgut used for the contractual net work within the rim has consisted of a single lace of a length sufficient to meet the requirements of the area inclosed by the rim. Hence, if one or more strands snapped under the stress of use the racket had to be unstrung completely and re-strung with a new catgut, resulting in considerable expense and delay,—the operation of stringing being long and tedious, and the cost of the catgut laces being proportionate to their length and quality. In fact the re-stringing of the usual tennis racket, done by professional stringers in the larger cities to whom the rackets have to be sent for repairs, involves a cost approximately one third the average original cost of an ordinary racket, not to mention the inconvenience and delay caused by reason of transportation, etc., and as rackets in constant use may require replacing several times in the course of a season, or at comparatively short intervals of time, it is obvious that a simpler and cheaper method of construction, and repair and renewal, is a desideratum.

It is the main object of my invention to obviate this difficulty, and to so simplify the method of applying the strands of catgut to the rim that broken strands may be readily and immediately replaced by any person of ordinary skill, thus avoiding delay and expense of transportation, the necessity for the employment of professional skilled labor, and the inconvenience and loss of time heretofore involved in the re-stringing of a racket. Furthermore, both the initial cost, and the cost of repair, is greatly reduced by the utilization of catgut of relatively short lengths, and hence of reduced aggregate cost, as compared with a one piece

catgut lace such as heretofore deemed indispensable.

The invention consists in the specific construction and arrangement of parts described and claimed,—distinctive features being the use of relatively short lengths of catgut to form the cross strands of the reticulated striking surface, and the means of securing said strands to the rim, all as hereinafter fully set forth.

In the accompanying drawings,

Figure 1, is a side elevation of the main portion of a tennis racket embodying the essential features of my invention, the rim being broken away in part to show the strand fastenings;

Fig. 2, is an edge elevation of the parts shown in Fig. 1;

Fig. 3, is a view of a strand of the lace;

Fig. 4, shows details views, taken at right angles to each other, of one form of strand securing device;

Fig. 5, shows similar views of another form of strand securer adapted to the purpose;

Fig. 6, is a cross section on a larger scale taken through the rim on plane of line 6—6, Fig. 2;

Fig. 7, is an equivalent section of the other side of the rim showing the end of the twin strands shown in Fig. 6.

Fig. 8, is a sectional elevation in detail, showing another modification in the means of securing the end of a strand in position in the rim.

R, represents the rim of a tennis racket, attached in the usual way to a handle R', which is shown as broken away in Figs. 1 and 2 of the drawings.

S, S, are the strands of catgut or other suitable material which form the woven reticulated striking surface of the racket, it being understood that by the term "catgut" as herein used I mean to designate and include any suitable or practicable substitute for that material,—the word catgut being used in a figurative sense as well as representing the material ordinarily used for the purpose.

The rim is formed with the usual transverse perforations p, p, from periphery to inner surface, said perforations p, p, being connected in pairs by peripheral grooves g, as in the ordinary rim of a tennis racket, and which adapt the rim to be strung in the ordinary way by a single long lace if so de-

sired. But as before stated I propose to discard the single lace as heretofore used, and to substitute a plurality of shorter laces, or even single strands, secured independently to the rim R.

For instance s' , represents a single strand formed of a single short piece of catgut the ends of which are individually secured to and in opposite sides of the rim; s^2 , is an illustration of a single length of catgut forming two adjoining strands of the reticulated contact surface, the ends of which twin strands are secured on one side of the rim; while s^4 , is an illustration of a length of catgut forming four parallel and adjacent strands of said reticulated contactual surface, the ends of which length of catgut s^4 , are secured, one in the outer end of the rim as at a , and the other in a side portion a' , thereof, all as shown in Fig. 1. In the case of the lace s^4 , the rear end is strung through a side perforation p' , in and along a groove g' , (Figs. 1 and 2) back through a perforation p^2 , to perforation p^3 , and groove g^2 , to the point a' , above referred to.

In applying the strands one end of the length of catgut is knotted or otherwise enlarged to prevent its passage through the lateral perforations p , the other end is then threaded through the rim as required and then knotted or otherwise enlarged to afford suitable contact for a fastening plug q , which is forced into the peripheral recess r , in the rim within which said end of the strand is positioned.

By way of illustration, take the twin strands s^2 , s^2 , shown in the enlarged views Figs. 6 and 7: the end 1, (not yet knotted) of the catgut lace s^2 , s^2 , is first passed through the lateral perforation p'' , at the bottom of the recess r , on the left side of the rim R, and the lace drawn through said perforation p'' , until the knot 2, rests against the bottom of the recess r , as shown in Fig. 6; then the free end 1, of the lace is passed through the perforation p''' , in the other or right side of the rim (forming the strand 3) through the groove g' , through the perforation p'''' , (forming the bight 4) and back to the left side of the rim where it is passed through the perforation p^x , forming the strand 5). It is then formed with the knot 6, drawn taut, and bent in to the groove g , to form the bight 7, the knot 6, being tucked into the recess r , and secured therein by the insertion of the plug q , into the recess r , thereby also firmly locking the bight 7, in position against the bottom of the groove g . Thus secured, the bights 4 and 7 hold the strands 3 and 6 (s^2 , s^2) taut and firm, so that the elasticity and resilience of the strands will be fully utilized in play.

Where a single length of catgut is used for each strand, as in the case of the strands s' , s' , the knot at each end thereof is secured

within a recess r , in like manner by a plug q , fitting therein, as shown in Fig. 1, which also shows the securing of the ends of the four strand lace s^4 , in like manner.

The plugs q , may be of any desired form 70 and construction adapted to perform the function of locking devices for the ends of the catgut strands or laces, so that I do not limit myself in this respect, those shown in Fig. 4, being in the form of headed 75 wedges, while those shown in Fig. 5, are in the form of staples. These plugs q , fit snugly within the recess r , but may be quickly and conveniently removed therefrom by a point inserted (say) through the 80 adjacent groove g , and under the head or outer end of the plug q . Thus a broken strand, or strands may be removed and replaced without disturbing those still intact, and the operation and manipulation is so 85 simple as to be readily performed by a person of ordinary care and intelligence, and without the employment of a professional stringer.

Furthermore the cost not only of original 90 production, but also of subsequent replacement of broken strands is materially reduced because of the shortness of the lengths of catgut used and their relative cheapness.

Another advantage of my structure is that 95 the reticulated contactual surface as a whole is "quicker" than when composed of a single lace of catgut as heretofore. In other words its resilience is increased, and the reaction against the ball is more immediate 100 and effective.

I prefer to form the recesses r , r , alternately in position as related to the edges of the outer or peripheral face of the rim R, as shown in Fig. 2, so as to balance the rim 105 as regards strength and lightness; and in this connection it must be taken into consideration that the material of the rim removed in forming the recesses r , and perforation connecting grooves g , g , more than compensates for the weight of the securing plugs q , which are of light, open, structure and may be made of relatively light material, either metallic or non-metallic. Thus they may be made of aluminum, or a light 115 metallic alloy, or of wood, celluloid, or any other suitable substance as may be found most expedient.

When headed, as in Fig. 4, or in the form of staples, as in Fig. 5, it is obvious that the 120 outer extremities of the plugs q , are adapted to facilitate their being readily pried out of the recesses r , by a suitable pointed instrument; and such heads or outer extremities of said plugs may of course be variously 125 shaped to attain this end.

It is to be understood that by the term "plug" as herein used I mean to designate any form of driven securing device adapted to the purpose. Thus in Fig. 8, I show a 130

brad or wedge *q*, driven into one of the lateral perforations *p*, and a serrated lateral arm which clamps down the bight *8*, of the strand *S*, into the groove *g*,—the recess *r*, being dispensed with in this case.

5 What I claim as my invention and desire to secure by Letters Patent is,

1. In a racket of the character designated, an elastic resilient reticulated contactual medium consisting of cross strands comprising a plurality of laces independently secured to the rim, and wedge plugs formed with lateral projections adapted to clamp the end of a strand within the rim for the

15 purpose described.

2. In a racket of the character designated, an elastic resilient contactual medium consisting of a series of cross strands each se-

cured to the rim, and a wedge plug formed with a lateral projection adapted to clamp 20 the end of the strand to and within the rim, for the purpose described.

3. In a racket of the character designated, the combination of a rim formed with shouldered recesses to accommodate the ends 25 of a series of strands, said strands, and wedge plugs fitting in said recesses and formed with lateral projections adapted to clamp the ends of the strands against the shoulders in said recesses, for the purpose 30 described.

HENRY HOLDING.
